ELECTRIC HEATER

Filed Aug. 24, 1921

UNITED STATES PATENT OFFICE.

TRUMAN S. FULLER AND JOHN A. WARD, OF SCHENECTADY, NEW YORK, ASSIGNEES
TO GENERAL ELECTRIC COMPANY, A CORPORATION OF NEW YORK.

ELECTRIC HEATER.

Application filed August 24, 1921. Serial No. 494,941.

To all whom it may concern:

Be it known that we, TRUMAN S. FULLER and JOHN A. WARD, citizens of the United States, residing at Schenectady, county of 5 Schenectady, State of New York, have invented certain new and useful Improvements in Electric Heaters, of which the following is a specification.

This invention relates to electric heaters 10 and has for its object the provision of improved means for automatically opening the circuit of the heater at a predetermined temperature.

More specifically, our invention relates to 15 electric flat-irons in which a thermostatic element is provided for automatically operating a switch in the heating circuit to prevent excessive temperatures in the flat-iron. In carrying out our invention, we employ a 20 helical thermostatic element which is mounted in a recess within the heated body of the flat-iron. On top of the body of the flat-iron we mount a switch in the heating circuit which is operatively connected to the 25 thermostatic element so as to be opened upon the occurrence of a predetermined maximum temperature. The operative connection between the thermostatic element and the switch is provided with an adjustment 30 which can be set to cause the switch to be opened at the desired maximum temperature.

In the accompanying drawing, Fig. 1 shows a flat-iron constructed in accordance with our invention with the principal parts 35 in spaced relation; Fig. 2 is a diagrammatic representation of the heating circuit and automatic cut-out; Fig. 3 is a plan view of the electric switch in the heating circuit; Fig. 4 is a view in perspective of the spring 40 latch for the switch; Fig. 5 is a view in perspective of the movable switch arm; Fig. 6 is a view in perspective of the stationary parts of the switch; Fig. 7 is a view in perspective of the operative connection between the thermostatic element and the 45 switch, while Fig. 8 is a section along the line 8—8 of Fig. 6 looking in the direction of the arrows.

Referring to the drawing, the flat-iron 10 50 comprises a heated body consisting of a metallic sole plate 11 and a metallic pressure plate 12, and a cover 13 provided with a handle (not shown). The pressure plate 12

is adapted to be secured to the sole plate 11 with a suitable heating element 14 clamped 55 between. The heating element is insulated between two sheets of mica, and is provided with terminals 15 and 16. The cover 13 fits over pressure plate 12 onto sole plate 11, the parts being secured together by suitable 60 screws.

In the sole plate 11 is an elongated recess 17 in which is mounted a helical thermostatic element 18. The thermostatic element is mounted in spaced relation with the walls of the recess by means of a rod 19 which extends through the thermostatic element and is rigidly secured thereto at one end. The opposite end of the rod 19 is attached by means of a screw 19' to the plate 11. The thermostatic element is thus mounted so that it can freely rotate about rod 19 in response to changes of temperature. The free end 20 of the thermostatic element extends at right angles to rod 19 into a transverse intersecting recess 21.

The switching mechanism for the heating circuit is mounted on top of pressure plate 12 upon a metallic supporting plate 22, 80 which is secured in parallel spaced relation to the pressure plate by means of three down-turned projections 23, 24 and 25 forming legs. A U-shaped strip of metal 26 provided with two projections 27 and 27' is secured by means of a rivet to the right hand end of plate 22 and maintained in insulated relation to the plate by means of a strip of insulating material 26'. Projection 27 extends upwardly and bears a stationary contact 28, while projection 27' extends downwardly and is provided with a screw so as to form a convenient connection terminal for contact 28. A second U-shaped strip of metal 30 is secured in like manner in insulated relation to plate 22 and in spaced relation with contact 28. Strip 30 has an upwardly turned projection carrying a contact 31. The other end of strip 30 is folded back, as shown in Fig. 8, bent downwardly 95 and provided with a screw to form a convenient connection terminal 32 for contact 31.

Cooperating with stationary contacts 28 and 31 are two movable contacts 33 and 34 which are secured to opposite ends of a resilient metallic strip 35. The strip 35 is secured at 100 its middle by means of rivets to a switch

arm 36 and insulated from arm 36 by strips of insulating material 35'. Switch arm 36 is secured at one end by a screw 37 to plate 22 so as to be movable about screw 37 as an axis 5 to bring contacts 33 and 34 into engagement with contacts 31 and 28, respectively. The switch arm 36 is biased to open circuit position by means of a spring 38 wrapped around screw 37 and having its ends in engagement, respectively, with arm 36 and an upwardly turned projection 39 on plate 22. The movement of the free end of the switch arm is limited by means of two upwardly turned projections 40 and 41 on plate 22.

10 The switch arm 36 is held in closed circuit position by means of a latch 42 consisting of a strip of resilient metal bent as shown in Fig. 4 to have a latching projection 43 near one end and a right angle extension 44. The latch 42 has its longer end secured to plate 22 so that projection 43 extends normally through a rectangular opening 45 in the plate and projects slightly above it. Integral with switch arm 36 is 15 a right angle member 46 having an opening 47 therethrough. The member 46 rests on plate 22 so that opening 47 is above opening 45 in the plate. When switch arm 36 is moved to close circuit position, member 46 20 slips over projection 43 forcing it downward until it springs into opening 47 and engages member 46 so as to hold the switch arm in closed position. The member 46, as it 25 engages with latch 42, slides beneath an overhanging strip 48 secured to plate 22 and in this manner is held downward onto plate 22 against the pressure of latch 42 while 30 passing over the projection 43.

Latch 42 is operatively connected to the 35 thermostatic element 18 by means of a lever arm 49 which is pivotally supported on a bracket 50 secured to the lower side of plate 22, the point of support of lever arm 49 being nearer the left hand end. The lever arm 45 is supported in a rectangular opening 51 in the pressure plate, the right hand end of the lever arm being curved downwardly through the opening. The left hand end of the lever arm is connected by means of a 50 suitable link 49' to the extension 44 on latch 42, while to the right hand end of the lever arm is secured a screw 52 having a lock nut 53 by means of which the screw may be tightened in any adjusted position. When 55 the pressure plate 12 is assembled on the sole plate 11, screw 52 is directly above and in position to be engaged by the free end 20 of the thermostatic element. By means of arm 49 the thermostatic element is given an 60 increased leverage in tripping latch 42. The operation of the thermostatic element is therefore both positive and sensitive. Secured to a projection 55 on switch arm 36 is a push button 56 which is adapted to extend through an opening 57 in the cover 13

when the flat-iron is assembled. It will be observed that the switching mechanism is inclosed by the cover 13.

Terminal 15 of the heating element is connected permanently to the connection 27', 70 while terminal 16 is connected to main 58 leading to a suitable source of electric supply, the opposite side of which is connected through main 59 to terminal 32.

As thus constructed and arranged the 75 operation of our invention is as follows: When it is desired to heat the iron, button 56 is pressed inward until switch arm 36 is moved to closed circuit position and locked by latch 42. A circuit for heating element 80 14 is thus closed from supply main 58 through the heating element, contacts 28 and 34, metallic strip 35, and contacts 33 and 31 to supply main 59. The flat-iron now heats up and transmits its heat to the thermostatic 85 element. As the temperature of the flat-iron increases the thermostatic element is affected to rotate its free end 20 upwardly about rod 19, and at some predetermined maximum temperature arm 20 will engage 90 screw 52 and give it sufficient upward movement to move projection 43 downward and release switch arm 36, which moves about its pivot due to the influence of spring 38, thus opening the heating circuit through the 95 contacts. In order to again heat the flat-iron the heating circuit must be reclosed manually by pressing button 56, as previously described. By adjusting the position of screw 52, the switching mechanism 100 can be set to open the heating circuit at the desired maximum temperature.

It will be observed that we have provided 105 very simple, reliable, and economical means for automatically opening the heating circuit of a flat-iron in response to excessive temperature. The construction is such as to cause a quick break and thereby prevent injurious arcing at the contacts. The thermostatic element is mounted within the 110 heated body of the flat-iron near the ironing face and is consequently immediately responsive to the temperature of the heated body and particularly to the temperature of the ironing face, which is the part of the flat iron that it is desired to protect from overheating. By using a helical thermostatic element, which has a comparatively wide range of movement, the temperature setting 115 can be made with accuracy. This is a great advantage since the dangerous temperature of a flat-iron is but little higher than the working temperature.

The arrangement of both the switching 120 mechanism and the operative connection 125 with the thermostatic element on a single support which is attached to the body of the flat-iron provides for simplicity and economy in manufacture. The necessity for extremely accurate machine work in the 130

various parts of the switching mechanism, the thermostatic element, and the flat-iron is avoided by means of our adjustable operative connection between the thermostatic element and the switching mechanism.

In accordance with the provisions of the patent statutes, we have described the principle of operation of our invention, together with the apparatus which we now 10 consider to represent the best embodiment thereof, but we desire to have it understood that the apparatus shown is only illustrative and that the invention can be carried out by other means.

15 What we claim as new and desire to secure by Letters Patent of the United States, is,—

1. A temperature cut-out for electric heaters comprising in combination with a 20 heated body, a thermostatic element within said body, a supporting plate mounted on said body in spaced relation thereto, stationary and movable switch contacts mounted on said plate, a spring for biasing said 25 movable switch contact to open circuit position, a latch secured to said plate arranged to hold said movable switch contact in closed circuit position, and a lever arm secured to said plate having one end cooperating with said latch and the other end cooperating with said thermostatic element so as to be actuated by said thermostatic element to release said movable switch contact upon the occurrence of a predetermined temperature.

2. A temperature cut-out for electric heaters comprising in combination with a heated body, a thermostatic element supported within said body, a supporting plate 40 mounted on said body in spaced relation thereto, a pair of stationary insulated switch contacts in the circuit of said heater carried by said plate, a switch arm pivotally mounted on said plate, a resilient metallic 45 member attached to said switch arm and

insulated therefrom, a pair of movable contacts adapted to cooperate with said stationary contacts carried by said resilient member, a latch secured to said plate and adapted to engage said switch arm to hold 50 it in closed position, and a lever arm secured to said plate having one end cooperating with said latch and the other end cooperating with the thermostatic element, whereby the latch is stripped by the thermostatic element to open the circuit of said heater upon the occurrence of a predetermined temperature.

3. An electric flat-iron comprising a sole plate, a heating element therefor, a thermostatic element in thermal relation with said sole plate, a pressure plate above said sole plate, switch mechanism on said pressure plate having an opening to said sole plate, and operative connections from the 65 thermostatic element to the switch mechanism through said opening.

4. An electric flat-iron comprising a sole plate having a recess therein, a thermostatic element mounted in said recess, a pressure 70 plate having an aperture registering with said recess secured to said sole plate, an insulated heating element held between said plates, a switch biased to open position in the circuit of said heating element and 75 mounted on said pressure plate, a latch for holding said switch in closed position, and a lever arm having one end cooperating with said latch and the other end extending through said aperture and cooperating with said thermostatic element, whereby the switch is released to open the circuit of said heating element upon the occurrence of a predetermined temperature.

In witness whereof, we have hereunto set 85 our hands this twenty-third day of August, 1921.

TRUMAN S. FULLER.
JOHN A. WARD.
